CLAIM

The ornamental design for a seat leg, as shown and described.

DESCRIPTION

FIG. 1 is a perspective view of a seat leg showing my new design;

FIG. 2 is a side elevational view thereof, all other sides being identical thereto;

FIG. 3 is a top plan view thereof; and,

FIG. 4 is a bottom plan view thereof.

The broken line illustration of a sofa in FIG. 1 is for illustrative purposes only and forms no part of the claimed design.
